UNITED STATES PATENT OFFICE.

ANCEL B. STUBBINS, OF ALLIANCE, OHIO.

COLLAR BUTTON AND TIE ADJUSTER.

Application filed October 25, 1923. Serial No. 670,646.

To all whom it may concern:

Be it known that ANCER B. STUBBINS, a citizen of the United States, residing at Alliance, in the county of Stark and State 5 of Ohio, has invented certain new and useful Improvements in Collar Button and Tie Adjusters, of which the following is a specification.

This invention is in the way of a collar 10 button and tie adjuster, and the object of the invention is to provide a simple and efficient device for securing the necktie to the collar button in self-adjusted relation.

In the drawing—

15 Figure 1 is a front elevation of the device as in use for holding a tie in place, the tie being indicated in dotted lines and the device itself shown in solid lines;

20 Figure 2 is a front view of the device detached;

Figure 3 is a side view of the device detached;

Figure 4 is a rear view of a tie with the device secured thereto.

25 The invention consists of a sheet metal stamping embodying a button claw 1 adapted to hook over the top of the collar button 2 as mounted in the collar 3, and having an integral, depending hollow stem 4 closed 30 at the lower end, but open at the upper end, and provided with eyelets 5, whereby the device may be sewed to the back of the tie 6. A small coil spring 7 is set into the lower end of the stem 4, and slidingly 35 mounted in this stem and seated upon the

spring 7 is a pressure pin 8 with a button tab 9 turned perpendicularly outward at its upper end.

In use, the device is sewed or otherwise secured to the back of the tie. The button tab is pressed down. The claw is set down over the button and the button tab is then allowed to press upward against the button through the action of the spring; whereby the tie is securely locked to the 45 button and to the collar.

While I have herein described a certain specific manner and method of constructing and assembling the elements of my invention, it is understood that I may vary 50 from the same in minor details, not departing from the spirit of my invention, so as best to construct a practical device for the purpose intended, as defined in the appended claim.

55 I claim:

A device of the kind described, comprising a button claw adapted to engage the collar button; a hollow stem depending from the button claw; a coil spring seated 60 in the hollow stem; and a pressure pin seated in the hollow stem upon the spring, the pin having a button engaging tab at its upper end.

In testimony whereof I affix my signature.

ANCER B. STUBBINS.
